HENRY J. LUFF AND WILLARD J. LUFF, OF CLEVELAND HEIGHTS, OHIO; SAID HENRY J. LUFF ASSIGNOR TO SAID WILLARD J. LUFF

GAS-VENT T

Application filed April 13, 1929. Serial No. 354,738.

The present invention relates, as indicated, to a gas vent, and more particularly to a fitting adapted to be used to connect the vent pipe of any one of a series of stoves to a common flue, the fitting being especially designed to prevent the flow of condensed liquid from the products of combustion out of the flue. Further objects will appear as the description proceeds. To the accomplishment of the foregoing and related ends, said invention, then, consists of the means herein-after fully described and particularly pointed out in the claims.

The annexed drawing and the following description set forth in detail certain mechanism embodying the invention, such disclosed means constituting, however, but one of various mechanical forms in which the principle of the invention may be used.

In said annexed drawing:

The single figure is an elevation disclosing a flue and two slightly different types of fittings connected therein, one of said fittings being shown in vertical section. In apartment houses and similar structures, it is common practice to arrange those suites which are in vertical alignment with each other in exactly similar fashion. Thus, in the kitchen of a plurality of suites on different floors, the kitchen cabinet, the sink, the stove, etc., in each suite is arranged exactly above the corresponding fixture in the apartment on the floor below. It is thus possible to provide a single vent flue for the stoves of all the apartments in a single tier, and it is common practice to do so and to connect the vent pipes of the stoves in all such apartments to the same flue.

Some sort of fitting must, of course, be provided at each floor to permit the connection into the main flue of the stove pipe for that floor. A major objection to the fittings which have previously been provided has been that the liquid condensate from the products of combustion has had a tendency to flow outwardly, through the effect of surface tension, along the branch of the fitting to which the stove pipe is connected, with a consequent discoloration of the plaster about such point of connection. The fitting of the present inven-

tion entirely obviates the possibility of such difficulty.

Referring more particularly to the drawing, the reference numeral 1 indicates a section of a flue of the type which has just been described. A fitting 2 is connected to said section through the medium of an internally threaded hub 3 of slightly reduced internal diameter. A similar connection is indicated at 4 at the upper end of the fitting 2, and a leg 5 opens substantially horizontally from said fitting for the reception of a stove pipe. The fitting 2 is identical with the fitting 6 in most details, and consequently will not be described in detail. One of the fittings 2 is provided in the flue 1 adjacent each floor in the building with the exception of the lowermost floor adjacent which there is provided in the flue 1 a fitting 6 of slightly different characteristics.

As is illustrated in the drawing, the fitting 6 comprises a body member having an upper open end 7 which is of slightly reduced diameter and which is internally threaded for the reception of the lower end of the flue section 1. The lower internally threaded end 8 of the fitting 6 is materially reduced for the reception of the pipe 9, whereby there is formed a collecting cup 10 below the main body of the chamber 11 formed by the fitting 6. The fitting 6 may be considered a T having branches 7 and 8 and a leg 12.

As will be noted, the lower end 13 of the flue section 1 is, in the assembled position of the parts, precisely flush with the inner end 14 of the reduced portion 7.

When the illustrated system is installed, the various stove pipes will be inserted in the legs 5 and 12 of the respective fittings. Any liquid which condenses in the flue 1, for instance, between the fitting 2 and the fitting 6, will flow down the sides of the flue. Of course, this condensate collects in very small quantities, and consequently the flow is quite slow. When a given particle of moisture reaches the lower end 13 of the flue section 1, it will be seen that it encounters a sharp shoulder, and that it tends to form a globule or drop 15 depending from that shoulder. As is well understood the tendency is for this

globule to grow in size until its weight is sufficient to break the attraction between the liquid and the tube, rather than for the liquid to run horizontally across the shoulder 6 formed by the end 13 of the flue section 1 and the inner end 14 of the reduced portion 7 of the fitting. If, however, a portion of the liquid should run horizontally across this shoulder toward the leg 12, it will be received 10 by the groove 16 which is so formed as to cause the liquid to run downwardly and into the chamber 11 and collecting cup 10.

A still further protection is provided in that the interior surface of the leg 12 is 15 formed with a plurality of concentric tapered grooves 17, these grooves increasing in diameter from the inner to the outer end of the leg 12. As will be obvious, the taper of the respective grooves 17 causes the formation 20 of ridges 18 between each pair of grooves, and a rib 19 is formed adjacent the outer end of the leg 12. The grooves thus have two functions: viz., to prevent liquid from flowing from the inner to the outer end of the 25 leg 12, and to provide the ridges 18 of decreasing diameter from the outer to the inner end of the leg 12 whereby a secure line-type joint is provided between the stove pipe and the leg 12. A longitudinal groove 20 is 30 formed at the base of the leg 12, connecting the bases of the grooves 17 with each other and with the interior of the collecting cup 10.

It will thus be seen that the shoulder formed by the end 13 of the flue section 1 and 35 by the inner end 14 of the reduced portion of the fitting 6 operates to deter liquid from flowing from the chamber 11 into the leg 12, and that the grooves 16, 17, and 20 operate to prevent liquid from flowing from the inner 40 to the outer end of the leg 12.

The fitting of the present invention has a further feature which is considered to be of material value. Very often in buildings of the type in which the present fitting can advantageously be used, the stove used in each 45 suite is the property of the tenant. For this reason, or for other reasons, the stove pipe is often disconnected from the flue, and it is common practice, where a stove pipe is so disconnected to stuff the opening into the flue with paper or other material to prevent the flue gases from flowing outwardly into the room. Very often indeed such paper is 50 stuffed entirely too far into the opening and may extend into the flue partially to block the flue passage, thus preventing proper venting of the gases of combustion in other apartments. Sometimes, also, a wad of paper is 55 inadvertently pushed completely through the connecting leg and into the flue whence it cannot conveniently be removed. In order to make impossible all of these acts, I provide a cross-bar 21 extending across the leg 12 adjacent the inner end thereof. A single cross-bar 60 of this character is sufficient to prevent 65

the paper wadding usually used from being inadvertently pushed into the flue, or from being stuffed far enough into the leg 12 to interfere with flow through the flue. The cross-bar 21 further acts as a positioner for 70 the entered end of the stove pipe. Of course it is to be understood that our invention is not limited to the use of a single cross-bar, but that it includes also the use of a grating.

Other modes of applying the principle of 75 the invention may be employed instead of the one explained, change being made as regards the mechanism herein disclosed, provided the means stated by any of the following claims or the equivalent of such stated means be 80 employed.

We therefore particularly point out and distinctly claim as our invention:—

1. A gas-vent T having a leg adapted to be disposed in a substantially horizontal position, said leg being formed with a tapered annular groove to prevent flow of liquid along the interior surface of said leg to the outer end thereof. 85

2. A gas-vent T having a leg adapted to be disposed in a substantially horizontal position, said leg being formed in its interior surface with a tapered annular groove and with a longitudinal groove leading from the base of said annular groove to the interior of 90 the body of said T .

3. A gas-vent T having a leg adapted to be disposed in a substantially horizontal position, said leg being formed in its interior surface with a plurality of tapered concentric 100 grooves and with a longitudinal groove connecting the bases of said tapered grooves with each other and with the interior of the body of said T .

Signed by us this 11th day of April, 1929. 105
HENRY J. LUFF.
